UNITED STATES PATENT OFFICE

JOSEPH J. MARIOTTI, OF CHICAGO, ILLINOIS, ASSIGNOR TO DAPRATO STATUARY COMPANY, OF CHICAGO, ILLINOIS, A CORPORATION OF ILLINOIS

TABERNACLE

Application filed November 6, 1929. Serial No. 405,103.

My invention relates to safes or vaults and particularly to that type of safe or vault which may be used as a tabernacle.

Vaults of this type are usually comparatively small in size and placed in full public view and therefore must be strongly and heavily constructed without being cumbersome in order to prevent unwarranted entry thereto yet they should also be readily accessible to entry by authorized persons.

It is the purpose of my invention to provide a safe particularly suitable as a tabernacle which is strongly constructed, substantially burglar proof and yet readily accessible to authorized entry.

In accordance with my invention I provide a double walled vault with a door sliding between the walls and I further provide means for closing the space between the two walls when the doors are open in order to eliminate the possibility of dropping articles between the two walls when removing them from the interior of the vault.

In the illustrated embodiment of my invention I have shown a vault having a pair of doors which meet at the center and swing away from each other into the space between the two walls of the vault leaving a clear and entirely free opening into the vault. In this embodiment I prefer to provide a connection between the doors which causes them to be moved together, that is, to make it necessary to move one door only, which will automatically open the other door.

A more complete understanding of my invention will be had from the following description taken in connection with the drawings in which:

Fig. 1 is a front elevation of a vault or tabernacle constructed in accordance with my invention;

Fig. 2 is a plan view with the top removed illustrating the door operating mechanism;

Fig. 3 is a side elevation with a portion of the outer wall removed to illustrate the door supporting structure;

Fig. 4 is an enlarged vertical section on line 4-4 of Fig. 1;

Fig. 5 is a horizontal section on line 5-5 of Fig. 4;

Fig. 6 is a horizontal section on line 6-6 of Fig. 4;

Fig. 7 is a vertical section on line 7-7 of Fig. 4;

Fig. 8 is an enlarged detail showing the manner of covering and concealing the joints in the walls, and

Fig. 9 is a section on the line 9-9 of Fig. 4.

In the illustrated embodiment of my invention I have shown a double walled vault which in effect is one vault within another, the inner vault serving as the supporting medium for the outer shell and the doors.

The inner vault or safe chamber is constructed of a single sheet of metal 1 formed of sheet steel or some other suitable material and bent into a partial cylinder the vertical terminating ends of which are spaced to provide an opening or entry into the vault. For appearance and strength the chamber may be lined with a second sheet of metal 2 such as bronze, the ends of the two sheets being bound together by channel shaped strips 3. The upper edge of sheet 1 is secured by screws or by welding to a circular angle iron 4 to which is attached a top plate 6. The lower edge of sheet 1 is also secured to an angle ring 7 to which is attached a bottom plate 8 the vault chamber thus being defined by the wall 1, top 6 and bottom 8.

The top plate 6 and the bottom plate 8 carry spacers 9 which support the outer shell or casing. For this purpose an upper ring 11 and a lower ring 12 are secured to the spacers 9 by means of screws or the like.

An angular rim 13 is secured to the upper ring 11 and a similar angular rim 14 is secured to lower ring 12. To these angle rings are bolted or otherwise attached the outer shell 16 composed of two sections of sheet steel or other metal joined at the rear abutting edges by a strip 17.

The sections 16 comprising the outer shell are curved to form a substantially cylindrical body spaced from and concentric to the inner vault chamber and terminate at the front approximately adjacent the front ends of the inner wall 1. The outer sections 16 may be faced with facing sheets 18 of

bronze or other decorative metal which add 100

both to the appearance and strength of the tabernacle.

The front terminating edges of sheets 16 and 18 are finished off by trimming strips 19 which define the opening into the vault. To the horizontal lower flange of the lower ring 14 there is secured a base 21 which serves to support the tabernacle. The lower edges of the walls 16 and 18 are concealed and finished off by means of arcuate plates 22 the joints of which are concealed by cover plates 23. The space between the finishing strips 19 and below the lower plate 8 is closed by an arcuate plate 24 secured to the vertical flange of lower ring 14 being spaced therefrom by a spacing plate 26.

The upper end of the outer shell is closed by a dome-like structure secured to arcuate strips 27 surrounding the upper edges of walls 16 and 18 and similar in size and shape to strips 22, the joints of strips 27 being concealed by cover plates 28 in a manner similar to the base construction. The upper edges of strips 27 support a ring 39 which carries the dome-like top composed of sections 41, 42 and a top cover plate 43. The upper margin of the opening between front strips 19 is spanned by an arcuate front plate 44.

In order to close the opening through the two shells I provide a pair of swinging or sliding doors 46 and 47 secured to substantially triangular shaped door carriers, 48 and 49 respectively, curved to slide between the inner and outer shells. The carriers 48 and 49 extend above and below the ends 6 and 8 of the inner shell and are each rigidly secured to and supported upon a pair of arms 51, 52, and 53, 54. Arms 51 and 53 are pivoted to a bearing post 56 projecting upwardly from and being rigidly secured to substantially the center of the upper end plate 6 of the vault chamber. Arms 52 and 54 are pivoted to a bearing post 57 projecting downwardly from the center of end plate 8. The bearing post is provided with ball races to provide substantially frictionless bearing surfaces.

The doors 46 and 47 are secured to the carriers 48 and 49 respectively with the rear vertical edge of each door secured to the forward vertical edge of each carrier, that is, the doors project forwardly of the carrier. As previously described, the carriers extend above and below the end plates of the inner vault chamber but the doors stop at substantially the level of the lower plate 8.

In order to provide a flush or closed entrance into the vault a flat plate 50 is secured to the curved front plate 24 in horizontal position to extend across the entrance into the vault as a threshold and completely close the space between the plate 24 and the front edge of the end plate 8 the inner edge of the plate 50 being of course curved to fit closely adjacent the periphery of plate 8 thus providing a threshold plate leading into the vault.

In order that the two doors will open simultaneously and automatically, that is, movement of one door will open both, the upper arm 53 is provided with a projection 58 (see Fig. 2) which extends upon the opposite side of pivot 56 to the major portion of the arm 53. The exterior end of the projection 58 carries a pin 59 which engages in the slotted end 61 of a Z shaped lever 62 the opposite end of lever 62 being pivoted at 63 to the top plate 6. The arm 51 is also provided with a projection 64 somewhat shorter than the projection 58 and extending beyond the fulcrum point 56. The outer end of the projection 64 carries a pin 66 which engages one end of a link 67 the other end of link 67 being pivotally secured to lever 62 intermediate pins 59 and pin 63. From the above it follows that if arm 53 is moved to the right or in a counter-clockwise direction, pin 59 will move in a counter-clockwise direction and travel to the end of the slotted end of link 62 thus rotating link 62 in a counter-clockwise direction about its pivot 63. This movement will carry link 67 in a downward or inward direction (see dotted lines Fig. 2) thus rotating arm 51 in a clockwise direction about post 56. It is thus seen that if door 47 is moved to an open position, door 46 will be automatically moved to an open position. The same movements will take place if arm 51 or door 46 is opened in the first instance. In closing the reverse moves take place. The open and closed positions being shown in solid and dotted lines respectively in Figure 2.

In order that the doors may be securely locked in closed position the meeting edges thereof are provided with two angle strips 68 and 69 positioned to abut each other when the doors are in closed position. Strip 68 is provided with one or more perforations to receive a locking bar 71 forming part of a locking mechanism carried by strip 69. The locking mechanism comprises a vertical rod 72 to which the bar 71 is secured, the rod 72 being of sufficient length to project upwardly as at 73 through an aperture in the end plate 6. A stop 74 is provided to prevent the bar from rising too far. Rod 72 is actuated by a rack bar 76 which in turn is engaged by a pinion 77 the rotation of which is controlled by a standard tumbler lock 78. From the above it follows that when the proper key is inserted in the lock, pinion 77 may be rotated thereby thus actuating rack bar 76 and raising or lowering rod 72 and bar 71.

In order to limit the movement of the doors a pair of stops 79 are secured to the wall 1 which engages the rear slanting edges of the door carriers.

From the above description it can be seen that there is provided a substantially burglar proof vault comprising a vault chamber within an outer chamber having a pair of

doors which are readily and easily operable the doors being entirely concealed when the vault is open and the entire mechanism thereof being concealed both when the door is open and closed. The foregoing construction permits of a comparatively small vault or safe yet a strong safe which may be used as a tabernacle. The construction of the doors and the threshold plate provide a smooth and closed entrance into the vault thus eliminating the possibility of snaring articles as they are placed in or withdrawn from the tabernacle.

It is understood of course that many changes may be made in the details of construction without departing from the spirit and scope of the invention as defined in the claims appended hereto.

I claim:

1. A safe comprising a substantially cylindrical side wall, top and bottom end plates secured thereto, said side wall having an opening therein, a bearing post secured to each of the top and bottom end plates and a pair of arms pivoted to each of said posts, a pair of arcuate door carriers each being secured to one upper and one lower arm, a pair of arcuate doors secured to said carriers and arranged to project therefrom, said doors terminating at their lower ends above the bottom end plate and a plate extending beneath said door into close proximity to said bottom plate, said doors being arranged to swing over said plate and in front of said opening to close the same.

2. A safe comprising an inner wall enclosing a vault chamber and an outer wall spaced therefrom and substantially surrounding said inner wall, said walls having aligned openings leading into said chamber, a pair of door carriers, and a pair of doors secured to said door carriers and projecting laterally therefrom, said doors being movable into closed position in front of said openings and mounted for sliding movement with said carriers into open position between said walls.

3. A safe comprising a cylindrical wall and top and bottom walls, said walls enclosing a vault chamber, said cylindrical wall having an opening therethrough leading into said chamber, arcuate door carriers pivoted to the top and bottom walls and having portions thereof extending above and below the vault chamber and doors secured to said carriers and projecting laterally from said extended portions of said carriers, said doors being slidable with said carriers into closed position with the doors in front of said opening and into open position with the doors adjacent the cylindrical side wall.

4. A safe comprising an inner side wall, a top plate and a bottom plate, said wall and plates being arranged to enclose a vault chamber, an outer wall spaced from and substantially surrounding said inner side wall,

said outer wall and side wall having aligned openings constituting an entry into said chamber, a sliding door pivotally mounted about a pivot substantially removed from the door for sliding movements to a position in front of said entry when in closed position and to a position between said walls when in open position, and means extending outwardly from said chamber at the entry thereinto substantially flush with the bottom plate thereof to form a threshold at said entry, said means extending beneath said door when in closed position.

5. A safe comprising an inner side wall, a top plate and a bottom plate, said wall and plates being arranged to enclose a vault chamber, an outer wall spaced from and substantially surrounding said inner wall, said side wall and outer wall having aligned openings constituting an entry into said chamber, a pair of arms pivoted to each of the top and bottom plates, door carriers connecting each of said top arms to one of said bottom arms, a pair of doors secured to said door carriers, said doors being slidable to closed position in front of said entry and into open position between said side walls, and means extending outwardly from said chamber at the entry thereinto substantially flush with said bottom plate, said means extending beneath said doors when in closed position.

6. A safe comprising a substantially cylindrical side wall, top and bottom end plates secured thereto, said walls and plates providing a vault chamber, said side wall having an opening therethrough leading into said chamber, a bearing post secured to each of the top and bottom end plates without the chamber, a pair of arms pivoted to each of said posts, a pair of arcuate door carriers extending above and below said top and bottom plates, each of said carriers being secured to one upper and one lower arm, a pair of arcuate doors secured to said carriers with the bottom edges of said doors terminating substantially in the plane of said bottom plate, said doors being adapted to slide in front of said opening to close the same in closed position and adjacent said side wall in open position.

7. A safe comprising a substantially cylindrical side wall and top and bottom end plates secured thereto, said side wall and plates being arranged to enclose a vault chamber, an outer wall substantially surrounding said side wall and spaced therefrom, said side wall and said outer wall having aligned openings leading into said chamber, a bearing post secured to each of the top and bottom end plates, door carriers pivoted to said posts and a pair of arcuate doors secured to said door carriers and arranged to lie between said walls when in open position and to meet substantially at the center of said opening when in closed position, and means

connecting said doors for automatic simultaneous operation, said means comprising a lever secured to a fixed pivot upon one of said end plates, said lever having a sliding connection to one of said door carriers and a link pivoted to the other of said door carriers and to said lever at a point intermediate the ends of the latter.

In witness of the foregoing I affix my signature.

JOSEPH J. MARIOTTI.
